UNITED STATES PATENT OFFICE

WILLIAM M. GOLDSMITH, OF CINCINNATI, OHIO, ASSIGNOR TO THE GOLDSMITH METAL LATH COMPANY, OF CINCINNATI, OHIO, A CORPORATION OF OHIO

CEILING ELEMENTS FOR CONCRETE FLOOR CONSTRUCTION

Application filed August 4, 1926. Serial No. 127,149.

This invention relates to concrete floor structures in which arched metal tiles and strips of metal lath are employed for the purpose of forming a concrete floor, beams and a ceiling structure for the floor below at one portion, and has for an object the provision of means whereby to retain the said elements in a proper relation throughout the construction of the floor.

10 Another object is to provide a metal lath structure for receiving and positioning the metal tiles or domes which will preclude any spreading or displacement of the tiles when said tiles are under the pressure of the weight 15 of wet concrete.

These and other objects are attained by the means described herein and disclosed in the accompanying drawings, in which:

Fig. 1 is a fragmental perspective view of a 20 floor under construction and having embodied therein devices of my invention.

Fig. 2 is a perspective view of a metal lath of my invention.

Fig. 3 is a cross sectional view on line 3—3 25 of Fig. 1.

In constructing floors embodying my invention, a series of metal laths 6 each having upturned opposite ends 7 each aligned to form a continuous surface and having their 30 opposite ends supported upon soffits 8. The soffits 8 are supported on shoring members 9. In constructing floors according to this invention, the use of the usual temporary flooring is eliminated, the metal laths being placed 35 side by side in rows to span the spaces between the soffits 8. Metal tiles or domes 10 are positioned upon the rows of tiles with the lower edges 11 of said tiles positioned against the inner faces of upturned ends 7 of the laths, 40 thereby aligning the tiles without further effort and retaining the ends thereof against displacement. The adjacent ends of adjacent rows of laths 6 and tiles 10 used therewith 45 form troughs in which suitable reinforcing rods (not shown) may be placed and into which troughs concrete enters when the floor is poured for forming uniform rectilinear beams 12. As will be noted in Fig. 3, the concrete of the beam looks the upturned ends 50 7 of the laths 6 in said beams so that when

the concrete sets and the temporary support structure is removed a plane ceiling surface remains. A plaster finish 13 may then be applied over the exposed bottom faces 14 of the beams and the bottom faces of the laths 55 for producing a finished ceiling.

The lath 6 comprises a rectangular sheet of metal having spaced longitudinal ribs 15 formed therein and between which ribs the metal is perforated. The metal is not removed from the perforations 16 but is upwardly struck around the said perforations to form flanges 17. In forming the ends of the laths 6 the ribs 15 are flattened adjacent each end to form straight plane bottoms 18 65 for parallel troughs 19 along the ends of the tiles. The upturned ends 7 form the outer walls of the troughs while the substantially vertical ends 20 of the ribs form the inner wall thereof. As previously explained, the 70 edges 11 of the side walls of the tiles or domes 10 are seated and aligned in the troughs 19. In order to provide a substantial positioning means for both sides of the side walls of the tiles 10 there are provided lugs 75 21 at each end of each rib 15. The lugs 21 are struck from the top faces of the ribs and extend upright from the top of said edges 22 of the ribs 15. By reference to Fig. 3 it will be apparent that the combined operative 80 height of end walls 20 of the ribs and the outermost perpendicular edges 23 of lugs 21 is substantially the same as that of the upturned ends 7. In this manner the result attained in supporting and positioning the side walls of 85 the tiles is had without necessitating a special type of metal lath for the purpose, and at the same time a great saving of metal is effected. It will be observed that the lugs 21, 90 by reason of their position at the edges of ribs 15, are in reality a continuation of the side walls of the ribs and are consequently of greater strength and effectively resist any direct pressure of the tiles and concrete. The 95 effective height from the bottom of the troughs to the top of lugs 21 precludes any possibility of the side walls of the tiles creeping upwardly under the pressure of wet concrete, so that there is eliminated any possi- 100

bility of displacement of the tile walls toward one another.

I claim:

1. As a new article of manufacture, a metal lath having upturned ends, longitudinal ribs which are closed at the ends of the laths and are flattened adjacent to the upturned ends to provide transverse grooves, and lugs struck from the body of the ribs adjacent the ends thereof, said lugs extending in a plane with certain walls of the ribs.
2. As a new article of manufacture, a metal lath having longitudinal ribs extending upwardly from one face thereof, upturned ends on the laths extending above the top of the ribs, and lugs, struck from the body of the ribs and uniformly spaced from the upturned ends, the top edges of the lugs extending substantially above the tops of the ribs.
3. As a new article of manufacture, a metal lath, upturned ends on said lath and upturned longitudinally disposed lugs struck from the body of the lath and having their outermost edges spaced inwardly of the upturned ends, the ends and the lugs forming positioning and retaining means of substantially uniform height providing support on opposite sides of the walls of metal tiles and providing a relatively shallow plaster receiving recess intermediate said supporting means.
4. As a new article of manufacture a metal lath having upturned ends, reinforcing ribs for the lath serving as relatively low abutments spaced interiorly of the upturned ends, and lugs struck upwardly from said ribs to increase the effective height of the abutments.
5. In a device of the class described a metal lath having end flanges, reinforcing ribs for the lath and spaced from the flanges to provide abutments relatively lower than said flanges and means to increase the effective height of said abutments.

In testimony whereof, I have hereunto subscribed my name this 2nd day of August, 1926.

WILLIAM M. GOLDSMITH.
